UNITED STATES PATENT OFFICE.

ALBERT GOTTSCHALK, OF NEW YORK, N. Y., ASSIGNOR TO NATIONAL PNEUMATIC COMPANY, OF NEW YORK, N. Y., A CORPORATION OF WEST VIRGINIA.

MOTOR FOR DOOR-OPERATING MECHANISM.

1,277,061.

Specification of Letters Patent. Patented Aug. 27, 1918.

Application filed September 6, 1916. Serial No. 118,724.

To all whom it may concern:

Be it known that I, ALBERT GOTTSCHALK, a citizen of the United States, residing at New York, in the county and State of New York, have made a certain new and useful Invention in Motors for Door-Operating Mechanism, of which the following is a specification.

This invention relates to door operating mechanism, and particularly to electrically controlled pneumatic door operating motors.

The object of the invention is to provide a simple and efficient electrically controlled door operating mechanism wherein the full operation of the motor is secured with but momentary manipulation of the control switch.

A further object of the invention is to provide in connection with an electrically controlled pneumatic motor, a circuit locking device which is pneumatically controlled.

A further object of the invention is to provide a pneumatically operated circuit locking device which is placed in operation by the initial closing of the circuit.

A further object of the invention is to provide an adjustable device for use in closing the door, or operating the motor in one direction, which requires manual operation of the motor for a predetermined portion of the closing movement of the door, or of the movement of the motor, before controlling circuit is closed to electrically complete the closing movement of the door, or the movement of the motor.

Further objects of the invention will appear more fully hereinafter.

The invention consists substantially in the construction, combination, location and relative arrangement of parts, all as will be more fully hereinafter set forth, as shown by the accompanying drawing, and finally pointed out in the appended claims.

Referring to the drawings:-

Figure 1 is a view in side elevation, partly in section, of an electrically controlled pneumatic motor and pneumatically controlled circuit locking device embodying my invention.

Fig. 2 is a top plan view of the same partly in section taken on the line 2-2, Fig. 1 and looking in the direction of the arrows.

Fig. 3 is an end sectional view taken on the line 3-3, Fig. 1. 55

Fig. 4 is a sectional view of the end plate shown in section in Fig. 1.

Fig. 5 is a wiring diagram of the circuit control of the motor.

Fig. 6 is a horizontal sectional view of a modified structure of pneumatic circuit control device embodying my invention. 60

Fig. 7 is a sectional view taken on the line 7-7, Fig. 6, and looking in the direction of the arrows. 65

Fig. 8 is a sectional view of a well known type of magnet valve.

The same part is designated by the same reference numeral wherever it occurs throughout the several views. 70

Reference numeral 6 designates generally a standard double piston rack and pinion pneumatically operated motor, well known in the art, and such as is shown and described in my Patent No. 1,065,324, issued 75 to me on the 17th day of June, 1913. In this structure, the gear casing is shown at 8, the gear shaft at 9 and the door operating connection 10' attached thereto.

In accordance with my present invention 80 I provide the top of the cylinder casing 6 with suitable flat bases 10, two on each side of the gear casing 8 as shown. I also provide two conduits one on each side of the cylinder, and extending the length thereof, 85 in any suitable way, for example, by casting conduits 11 and 12 into the cylinder body as shown. It is understood, however, that I am not to be limited to this detail.

I provide two pneumatically operated circuit controllers, indicated generally at 13, which are adapted to rest on the bases 10, and to be suitably secured thereto in air tight connection therewith, as shown. 90

The cylinders 6 are provided with suitable heads designated by reference numeral 14 which form the operating fluid pressure inlet, and which are secured to the cylinders by suitable bolts 19. The heads 14 are each provided with a passage 15 connected to 100 suitable source of fluid pressure supply, as through passage 16 which is registered therewith. The passage 15 is in communication with the inlet of the usual form of magnet valve, the outlet of which magnet 105 valve is in communication with the passage

18 of the cylinder head 14 which leads through port 20 into the cylinder 6 to operate the piston therein. Communicating with the inlet passage 18 within the cylinder 5 head, is a passage 21 which communicates with a passage 22 formed in the end base portion 10 of the cylinder 6, and which passage in turn communicates with passage 23 formed in the body of the pneumatic circuit control device 13, to allow the fluid pressure to enter chamber 24 therein.

In Fig. 8, I show a common form of magnet valve which may be employed in accordance with my invention. These magnet valves are now standard equipment and well known in the art and as a specific construction of the same involves no part of my present invention, I will merely briefly describe the same as comprising the case 90 15 inclosing the coil 91 which are controlled by the contacts 92, and through the core of which extends the plunger 93 equipped with a valve head 94 laid normally on a seat 95 by means of a spring 96. Fluid pressure is admitted to port 97 from passage 15, and when the valve head 94 is unseated the fluid pressure flows through passage 98 into communication with the passage 18. When the valve head 94 is seated due to deenergizing 20 the magnet by opening the circuit thereof, and also due to the action of the spring 96, the passage 98 is thereby placed in communication with the exhaust port 99 as will be readily understood and the exhaust port 99 is in communication (see Fig. 4) with the 25 passage 38 port 37 and conduit 11 at one end. Conduit 12 is likewise in communication with the exhaust port of the magnet valve at the opposite end of the motor.

40 The pneumatic circuit control device 13 comprises, in my preferable form, a cylindrical casting as shown with a chamber 24 at one end and a relatively large chamber 25 at the other end. I prefer to bore these 45 chambers the required size and to close the aperture caused thereby in the end walls of the cylinder by suitable plugs 26. Differential pistons 27, 28 operate in the respective chambers and are connected by a common rod 29 on which is loosely mounted a 50 conducting ring 30 insulated from the rod 29 by suitable insulating bushing 31. The conducting ring 30 is adapted to slide along the rod 29 against the compression action 55 of a spring 32 when pressure is admitted behind the smaller piston 27. It will be noted that the device 13 on the left hand side of the gear casing 8 is positioned with the larger piston 28 adjacent the gear casing 60 8. The device on the right hand side of gear casing 8 is identical in structure, and operation, and is likewise positioned with its larger piston adjacent the gear casing. Circuit terminals 35, 36, of the control circuit 65 of door operating motor project into the cyl-

inder 13, and the function of the conducting ring 30 is to complete the circuit between the terminals 35, 36, as will be more fully hereinafter set forth.

The conduit 12, hereinbefore referred to 70 communicates at one end with port 37 of the motor casting and through passage 38 to the exhaust of the magnet valve at the other end, the conduit 12 communicates through passage 41 to chamber 24 of the 75 casing 13. A passage 39 also establishes communication between conduit 12 and chamber 25 of the right hand casing 13, which, as above stated is nearest the gear casing 8. The conduit 11 is provided with 80 identical passages but of reversed direction. That is the right hand end of the conduit communicates with the right end of the right casing 13, and the conduit communicates with the chamber 25 of the casing 13, and with the magnet valve as above explained. Each of the chambers 25 are also provided with a passage 40 leading through the base 10 into the main motor chamber, as shown. I prefer to control this passage by a ball 85 check, in one embodiment of my invention, as illustrated. Thus it will be seen that if the magnet valve at the left end of the motor is energized to admit pressure to the left end of the cylinder 6, conduit 12 is closed at 90 its right end and open to the fluid pressure at its left end, while conduit 11 is open to exhaust. Should the magnet valve at the 95 right end be energized, as will be later described, the conduit 12 is thereby opened to 100 exhaust, and the conduit 11 closed and placed in communication with the source of fluid pressure through the magnet valve.

From the foregoing it will be seen that 105 when fluid pressure is admitted into the main cylinder to cause the main piston to travel to the right, fluid pressure also passes through passages 21, 22 into chamber 24 thereby causing the pistons 27, 28 to move toward the right. This causes the contact or conducting ring 30 to close the circuit between terminals 35, 36, and to maintain such circuit closed as long as pressure is admitted. At the same time, conduit or 110 passage 12, is in communication with chamber 24 through port 41, and thus pressure is admitted through port 39 to the chamber 25 of the device 13 on the right hand side of gear casing 8, thus maintaining the contact ring 30 of that device, which is normally out of contact with its terminals 35, 36, out of contact therewith, and preventing it accidentally or otherwise, from establishing 115 its circuit. As soon as the piston within the main casing 6 passes and uncovers the port 40, it will be seen that the pressure will be equalized on each side of device 13, that is, there will be a pressure behind the piston 28 equal to the pressure behind the piston 27. The piston 28 being larger in area, 120 125 130

however, the pistons are forced to the left, breaking the circuit between the terminals 35, 36, thereby breaking the circuit controlling the magnet valve, and shutting off the supply of fluid pressure.

In Fig. 5 I show a wiring arrangement illustrating the electrical control of the motor wherein 50 designates the source of current 51 and 52 designate generally the magnet valves which control the supply of fluid pressure to the left and right hand pistons, respectively, and 53, 54 designate the push buttons or switch control of the respective magnet valves.

The terminals 35, 36, are the terminals controlled by the conducting ring 30 of the control device 13. Thus it will be seen that if the left hand piston is operated, say to close the door, the push button or other switch 53 is momentarily closed, thereby establishing a circuit through the magnet valve 51, which then admits fluid pressure through port 20 into the operating chamber of the motor, and coincidentally admits the fluid pressure into chamber 24 of device 13, causing the pistons 27, 28 to move to the right, thereby closing the circuit between terminals 35, 36, and maintaining said circuit closed until the door closing movement is completed. It will be seen that a momentary closing of the switch 53 is all that is necessary to secure the operation of the device 13 which maintains the circuit of the magnet valve 51 closed and the magnet valve energized. The operation of the reversing magnet valve 52, and its device 13 it will be seen, is identical with that of 51.

It is sometimes desirable to require manual operation to start the closing movement of the door, other than the pressing of the reversing button, for a portion of its closing movement. I provide for this by mounting on the shaft 9 a lug 60 having secured thereto a short arm 61. The lug 60 is positioned on the shaft 9 at any desired angle, for example by the set screws 62. Suitably secured to the cylinder 6 by bracket 63 is a button switch 64 directly in the path of travel of the arm 61. The arm 61 is pivoted to the lug 60, as at 65 and is provided with a rounded edge 66 so that when the arm 61 travels clock wise, it will yield or rock when passing the button 64, but on its return travel will not yield or rock, and will thereby depress the button 64 and close the switch indicated at 67 in Fig. 5. Thus it will be seen that the closing movement of the door may necessitate manual operation for any portion thereof, according to the position of the lug 60 on shaft 9, before the switch 67 becomes closed to energize the magnet valve 51, and consequently to operate its associated device 13, and the conductor 30 to maintain

the circuit between terminals 35, 36, throughout the completion of the door closing movement.

It is necessary, in the devices 13, to prevent the fluid pressure supplied to chamber 25, behind the larger pistons 28, through ports 39, from passing into the cylinder 6 of the main motor through ports 40. To prevent this, I employ a ball check, as shown best in Fig. 1.

In Figs. 6 and 7, I show a modified structure of device 13, wherein I make the connecting rod 29 of insulating fiber, sunk in the pistons 27, 28. The spring 32 is in this instance insulated from the conductor 30, by a mica or other suitable insulating washer 31. In this arrangement I avoid the use of a ball check by embodying a double piston arrangement as shown at 28, 28^a. A spring 70 housed in the nut 26 and piston 28^a normally tends to keep the circuit open between terminals 35 and 36. It will be seen that due to the double piston arrangement, no fluid pressure entering port 39 can pass to port 40 and thence to the cylinder of the main motor.

It will be further seen that if it is desired to reverse the motor during its operating movement in one direction, that is, for example, if the motor is closing the door, and it is desired to again open the door before the closing movement thereof is completed, the circuit controlling the device 13 which is not closing the path of travel of current between terminals 35, 36, may be closed. By closing this circuit, fluid pressure is admitted to open the switch device 13 which up to that time has been closed, and to close the other switch device 13 which up to that time has been open. Thus it will be seen that the main motor can be readily and quickly reversed any time during the operation thereof, which feature of quick control contributes largely to the safety of the motor in operation.

Having now set forth the objects and nature of my invention, and having shown and described various embodiments thereof, what I claim as new and useful, and of my own invention, and desire to secure by Letters Patent is,—

1. The combination with a fluid pressure operated motor, a valve for controlling the supply and exhaust of fluid pressure to and from said motor, an electric device to control said valve, a normally open circuit for controlling said electric device, of means for momentarily closing said circuit and fluid pressure means operated thereby for maintaining said circuit closed.

2. The combination with a fluid pressure operated motor, a valve for controlling the supply and exhaust of fluid pressure to and from said motor, an electric device to control said valve, a normally open circuit for

controlling said electric device, of means for momentarily closing said circuit and a fluid pressure device operated thereby for maintaining said circuit closed, and means 5 for admitting fluid pressure to said motor and to said device simultaneously.

3. The combination with a fluid pressure operated motor, a valve for controlling the supply and exhaust of fluid pressure to and 10 from said motor, an electric device to control said valve, a normally open circuit for controlling said electric device, of means for momentarily closing said circuit and fluid pressure means operated thereby for 15 maintaining said circuit closed and means for breaking said circuit when said motor has completed its operation.

4. The combination with a fluid pressure operated motor, a valve for controlling the supply and exhaust of fluid pressure to and 20 from said motor, an electric device to control said valve, a normally open circuit for controlling said electric device, of means for momentarily closing said circuit and means 25 operated thereby for maintaining said circuit closed and fluid pressure operated means for breaking said circuit when the motor has completed its operation.

5. The combination with a fluid pressure 30 operated motor, of a magnet valve to control the supply of fluid pressure to said motor, a normally open circuit for controlling said magnet valve, a fluid pressure operated switch for controlling said circuit, and 35 means controlled by the initial momentarily closing of said circuit for operating said switch.

6. The combination with a fluid pressure 40 operated motor, of a magnet valve to control the supply of fluid pressure to said motor, a normally open circuit for controlling said magnet valve, a fluid pressure operated switch for controlling said circuit, and means controlled by the initial momentarily 45 closing of said circuit for operating said switch, and means controlled by the completion of the operation of said motor, for opening said switch.

7. In a door operating device, the combination 50 with a fluid pressure operated motor, a valve for controlling the supply and exhaust of fluid pressure to and from said motor, of an electric circuit for controlling the operation of said valve, and means operated by the manual movement of said 55 motor for closing said circuit.

8. In a door operating device, the combination 60 with a fluid pressure operated motor, a valve for controlling the supply and exhaust of fluid pressure to and from said motor, of an electric circuit for controlling the operation of said valve, and means operated by the manual movement of said 65 motor for closing said circuit and fluid pressure actuated means for maintaining said

circuit closed until the end of the movement of said motor.

9. In a door operating device, the combination with a fluid pressure operated motor, a valve for controlling the supply 70 and exhaust of fluid pressure to and from said motor, of an electric circuit for controlling the operation of said valve, and means operated by the manual movement of said motor for closing said circuit and fluid pressure actuated means for maintaining said 75 circuit closed until the end of the movement of said motor, and means for breaking said circuit when said motor has completed its movement.

10. In a door operating device, the combination with a fluid pressure operated motor, a valve for controlling the supply and exhaust of fluid pressure to and from 80 said motor, of an electric circuit for controlling the operation of said valve, and means operated by the manual movement of said motor for closing said circuit and fluid pressure actuated means for maintaining said circuit closed until the end of the movement 85 of said motor, and fluid pressure actuated means for breaking said circuit when said motor has completed its movement.

11. The combination with a double piston motor, of an electric valve for controlling 90 the supply of fluid pressure thereto, a circuit for controlling said valve, terminals arranged in said circuit, fluid pressure actuated means for connecting said terminals, said means and said motor receiving said 100 fluid pressure coincidently and from a common source.

12. The combination with a fluid pressure operated motor, a valve for controlling the supply and exhaust of fluid pressure to and 105 from said motor, electric devices to control said valve, normally open circuits for controlling said electric devices, of means for momentarily closing one of said circuits, and fluid pressure means operated thereby for 110 maintaining said circuit closed, and means for momentarily closing the other of said circuits and means operated thereby for opening said first mentioned circuit.

13. The combination with a fluid pressure 115 operated motor, a valve for controlling the supply and exhaust of fluid pressure to and from said motor, electric devices to control said valve, normally open circuits for controlling said electric devices, of means for momentarily closing one of said circuits, and means operated thereby for maintaining 120 said circuit closed, and means for momentarily closing the other of said circuits, and fluid pressure means operated thereby for 125 opening said first mentioned circuit.

14. The combination with a fluid pressure operated motor, a valve for controlling the supply and exhaust of fluid pressure to and 130 from said motor, electric devices to con-

- trol said valve, normally open circuits for controlling said electric devices, of means for momentarily closing one of said circuits, and means operated thereby for maintaining 5 said circuit closed, and means for momentarily closing the other of said circuits to operate said last mentioned means to open said first mentioned circuit, and to maintain said first mentioned circuit open.
- 10 15. The combination with a fluid pressure operated motor, a valve for controlling the supply and exhaust of fluid pressure to and from said motor, electric devices to control
- said valve, normally open circuits for controlling said electric devices, of means for 15 momentarily closing one of said circuits, and means operated thereby for maintaining said circuit closed, and means for momentarily closing the other of said circuits to operate said last mentioned means to open 20 said first mentioned circuit, and to maintain said second circuit closed.

In testimony whereof I have hereunto set my hand on this 25th day of August A. D., 1916.

ALBERT GOTTSCHALK.
